(57) **CLAIM**

The ornamental design for “digital media adapter,” as shown and described.

DESCRIPTION

FIG. 1 is a perspective view of the design for the “digital media adapter” front bezel;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of “digital media adapter” is for the purpose of illustrating environmental structures only and forms no part of the claimed design.
